UNITED STATES PATENT OFFICE.

MARIE A. STARGARDT, OF RICHMOND, VIRGINIA.

DOOR LOCK.

Application filed September 27, 1922. Serial No. 590,895.

To all whom it may concern:

Be it known that I, MARIE A. STARGARDT, a citizen of the United States, residing at Richmond, in the county of Henrico and State of Virginia, have invented new and useful Improvements in Door Locks, of which the following is a specification.

This invention relates to improvements in fastening devices for hinged members and is especially adapted for use upon doors.

An object of the present invention is the provision of a fastening device by means of which a door or lock member may be held in a partly open position in a manner to permit of the door being readily closed, but held against further opening movement.

Another object of the invention is the provision of a device of this character, which, when in use, may be released from one side only by persons not in possession of a proper key, but may be readily opened from either side with the use of a key.

With the above and other objects in view, the invention further includes the following novel features and details of construction, to be hereinafter more fully described, illustrated in the accompanying drawings and pointed out in the appended claim.

In the drawings:

Figure 1 is a fragmentary elevation showing the application of the invention.

Figure 2 is a sectional view on the line 2—2 of Figure 1 showing the door in closed position.

Figure 3 is a similar view with the door partly open, but held against further opening movement.

Figure 4 is a section on the line 4—4 of Figure 2.

Figure 5 is a section on the line 5—5 of Figure 2.

Figure 6 is a detail sectional view illustrating the use of the key.

Figure 7 is a sectional view similar to Figure 4, but looking in an opposite direction.

Figure 8 is a detail perspective view of the key.

Referring in detail to the drawings, wherein like characters of reference denote corresponding parts, the reference character 10 indicates a portion of a door or other hinged member, a portion of the frame of which is shown at 11.

The invention which is shown as applied to the door 10 and frame 11, comprises a

bracket 12, which is rigidly secured to the frame by screws 13 and which carries an arm 14, having a pivot pin 15 rising from one end thereof. Mounted upon this pin 15 and slidable upon the arm 14 is a keeper 16, the latter being curved at one end and provided with an arcuate slot 17 to receive the pivot 15. The keeper 16 is thus pivotally and slidably mounted upon the arm 14 of the bracket 12. Secured to the pivot pin 15 is a spring arm 18, whose free end carries a substantially semi-circular lug 19. This lug is adapted to engage a beveled socket 20 provided in the keeper 16, the socket being arranged so as to be engaged by the lug 19 when the door is in its closed position. This holds the keeper against accidental movement. The keeper 16 is further provided with a beveled lip 21.

Secured to the hinged member or door 10 is an attaching plate 22, from which extends a stud or pintle 23, having at its outer end a head 24. Pivots mounted upon the stud or pintle 23 is a holding plate 25, which carries spaced apertured ears 26 for the passage of the pintle 23, whereby the plate 25 may be pivotally mounted upon the plate 22. The upper surface of the plate 25 is serrated or provided with longitudinally extending teeth and engageable with the upper surface of this plate is a similarly serrated locking arm 27, having openings in one end for the passage of bolts 28. These bolts pass through transverse slots 29 provided in the plate 25, so that the locking arm 27 may be adjusted with relation to the door 10. The outer end of the arm 27 is provided with a downwardly extending transversely disposed hook 30, the bill of which is spaced from the arm 27 so as to provide a notch 31. This hook is adapted to be received within an elongated slot 32 disposed transversely at the outer end of the keeper 16 and is capable of being inserted into and removed from the slot when the parts are in the position shown in Figure 2, that is, when the door 10 is closed. When the door is opened and the parts are in the position shown in Figure 3, it will be impossible to remove or disengage the locking arm 27 from the keeper, so that the door will be held against any further opening movement.

Assuming that the keeper 16 is in the position shown in Figure 2, the door may be moved to a closed position, whereupon the

bill of the hook will ride up the beveled lip 21 and the hook will enter the slot 32, dropping into the slot so that the notch 31 will be on a plane with the edge of the slot. 5 When the door is opened to the position shown in Figure 3, positive engagement between the locking arm 27 and keeper 16 is effected, and it will be impossible for a person upon the outside of the door to disengage the arm 27 and keeper 16 by inserting a hand through the door opening. When it is desired to open and close the door in the usual manner, the arm 27 may be moved to the position shown by the dotted lines in 10 Figure 1, one end of the arm engaging a stop 33 which is carried by the plate 22. This stop also serves to hold the arm 27 in position so that the hook will ride over the lip 21 as the door is closed. 15 20 In order that the door may be locked and afterward unlocked from the outside, by an authorized person, there is provided a key 34 which is illustrated in detail in Figure 8 of the drawings and whose use is shown in Figure 6. This key is substantially U-shaped and comprises a short arm 35 and a relatively long arm 36. The key is further provided with an opening 37, which is adapted to receive a pin 38 which extends 25 from the bottom of the plate 14 and is spaced slightly from the bracket 12. In the use of the key, the latter is mounted upon the pin 38 with the arm 36 positioned upon the keeper 16 and against the bracket 12, 30 the keeper having a lip 39 which may be engaged over the edge of the key. When in this position, the arm 35 of the key extends beneath the opening 32, so that the hook 30 will not pass downward through 35 this opening, but will remain in the position shown in Figure 6. When the parts are in the position shown in Figure 2, the door 40 may be opened and the key positioned as

above stated, whereupon, the door may be again closed so that the hook will keep the 45 position shown in Figure 6. Upon again opening the door, this hook will ride over the beveled edge of the opening 32 so as to release the locking arm from the keeper. 50

The invention is susceptible of various 55 changes in its form, proportions and minor details of construction and the right is herein reserved to make such changes as properly fall within the scope of the appended claim.

Having described the invention what is claimed is:—

A fastening device comprising in combination with a stationary member and a hinged member capable of being moved to an open position and a closed position, a keeper having an operative portion provided with an arcuate slot, said keeper mounted on said stationary member by a pivot extending through said slot whereby said keeper may have pivotal and sliding movement, a spring plate mounted upon the pivot for the keeper, a lug carried by said spring plate and adapted to enter a depression in said keeper plate to secure the same 60 against movement, an attaching plate secured to the movable member and having a stud projecting therefrom and forming a horizontal pivot, a locking arm pivoted on said stud, means carried by the locking arm 65 for engagement with the keeper, said means being such that said locking arm is disengageable from said keeper only when the movable member is in closed position, said locking arm adapted to be swung on said stud to an inoperative position away from the keeper, and means carried by the attaching plate for supporting the locking arm in its inoperative position. 70 75 80
